No. 788,709.

PATENTED MAY 2, 1905.

J. W. CUTLER.

MAIL CHUTE.

APPLICATION FILED JAN. 14, 1903.

Fig. 1.

UNITED STATES PATENT OFFICE.

JOSEPH WARREN CUTLER, OF ROCHESTER, NEW YORK.

MAIL-CHUTE.

SPECIFICATION forming part of Letters Patent No. 788,709, dated May 2, 1905.

Application filed January 14, 1903. Serial No. 139,019.

To all whom it may concern:

Be it known that I, JOSEPH WARREN CUTLER, of Rochester, in the county of Monroe and State of New York, have invented certain new and useful Improvements in Mail-Chutes; and I do hereby declare the following to be a full, clear, and exact description of the same, reference being had to the accompanying drawings, forming a part of this specification, 10 and to the reference-numerals marked thereon.

My present invention relates to mail-chutes, and has for its object to provide an improved closure for controlling the chute-openings at the various floors of a building whereby the 15 deposit of mail-matter into the chutes may be controlled by authorized persons only; and it consists in certain improvements and combinations of parts, all as will be hereinafter more fully described, the novel features being pointed out in the claims at the end of the specification.

In the accompanying drawings, Figure 1 is a vertical sectional view of a mail-chute embodying my improvements and showing two 25 of the mailing-apertures located on different floors, one open for the reception of mail-matter and the other closed. Fig. 2 is a front elevation of the mailing-section with a portion of the outer casing broken away. Fig. 3 is a 30 side elevation of a portion of the chute. Fig. 4 is a horizontal sectional view on the line $\alpha\alpha$ of Fig. 1. Fig. 5 is a vertical sectional view on the line $\gamma\gamma$ of Fig. 4. Fig. 6 is a vertical sectional view taken on the line $z z$ of Fig. 3, 35 showing the key in position. Fig. 7 is a perspective view of a portion of the lock.

Similar reference-numerals in the several figures indicate similar parts.

In the practical operation of mail-chutes of 40 the class to which my invention belongs it is oftentimes necessary to control access to the various mailing-apertures—as, for instance, where the mail box or receptacle is undergoing repairs or alterations—or when the buildings are very high and two or more chutes are 45 employed it is sometimes desirable to permit mail to be deposited from alternate floors only, and the chutes being under the control of the Post-Office Department provision must be

made to prevent unauthorized persons from 50 tampering with the chute or any of its parts, and my present invention relates to means for accomplishing this in the best and simplest manner.

The mail-chutes in connection with which 55 my invention is employed are of the type generally used and embody a conductor or casing 1, having the usual front plates 2, of glass, to permit inspection of the interior. The mailing-sections on each floor embody a casing 3 60 arranged between the ends of two of the glass front plates, being secured to the chute and to the backing in any suitable or usual manner, and is provided with a mail-receiving aperture 4 at its upper portion and also with 65 a front plate 5, preferably removable and secured in position in any suitable manner, and arranged within the casing is the downwardly-extending plate or apron 6, extending sufficiently far below the mail-receiving aperture 70 4 to prevent mail descending from above from catching in the mailing-section or interfering with the insertion of letters.

7 indicates a plate of sheet metal having flanges 8 on the sides, through which latter 75 passes a rod or pintle 9, secured in the sides of the casing, and upon which the plate may turn from the position shown in the upper part of Fig. 1 to that shown in the lower part. The upper end of plate 7 is bent outwardly 80 at an angle to form a lid or closure co-operating with the under side of the aperture 4, in the present instance being provided with a small separate plate 10, which may be a sign containing the word "Closed," if desired. This 85 plate 7 constitutes a lid or door, which is normally in the position shown in the upper part of Fig. 1, leaving the passage from the aperture 4 to the chute unobstructed, so that letters may be introduced and may pass into the 90 chute; but when moved to the position shown in the lower portion of Fig. 1 the aperture will be closed when for any purpose this is desired. At a point below the upper end the plate 7 is provided with inwardly-extending 95 prongs or ears 11, struck out of the sheet metal and bent, as shown, to prevent the entrance into the chute of large letters or pack-

ages, the ends of which might have been inserted in the aperture 4, serving in this respect the same functions as the corresponding projections illustrated in my prior patent, No. 430,626. For the purpose of operating and controlling the movement of the plate or door 7 I provide an arbor 13, journaled at its ends in the casing 3 and having rigidly secured thereto arms or projections 14, two being shown in the present instance and arranged centrally of the arbor a bracket 15, having a tongue or projection 16 thereon adapted to engage when the door is open with a lug or ear 17, preferably struck from the plate 7 and bent rearwardly and downward, as shown, these projections 16 and 17 engaging when the arbor is turned to the position shown in Fig. 1 for the purpose of positively holding the lid or door open.

18 indicates a leaf-spring, with its lower end secured to the plate 7 and its upper end extending in rear of the bracket 15 on the arbor, the tendency of the spring being to normally move the door to open the aperture.

While I prefer to employ the spring shown, it will be understood that other forms could be used, if desired, without departing from my invention.

From the above construction it will be seen that when the arbor is turned in one direction the door is permitted to be opened by the spring, or a positive connection could be employed, if desired, and it is held open by the bracket 15, and when the arbor is turned in the opposite direction the arms 14 will press the door to the position shown in the lower part of Fig. 1, holding it firmly closed and preventing the entrance of mail-matter to the chute, the ends of the arms 14 then passing beneath the projections 19, struck rearwardly from the plate 7, as shown particularly in Fig. 5.

For the purpose of operating and controlling the movements of the arbor I provide a removable operating handle or key 20 in the form of a flat plate like the ordinary Yale-lock key, having at its inner end projecting portions adapted to coöperate with suitable recesses in the end of the arbor 13, and beyond the end of the arbor I provide in or on the casing wards or interlocking portions, with which corresponding recesses in the edges of the key are adapted to coöperate, whereby the manipulation of the arbor by other means than the appropriate key is prevented. In the present construction the arbor 13 is journaled in inwardly-projecting bosses 21, formed or secured on the casing, and upon its outer end is secured a notched collar 22, (see Fig. 6,) with which the end of the key coöperates, and the guards or wards are held in position by a recessed boss or casing 23, secured to the casing by screws 24, inserted from the inner side of the main casing, so as to prevent the removal of the ward-

casing from the exterior, or instead of these screws other fastenings could be employed which would prevent the removal by unauthorized persons.

In Figs. 6 and 7 I have shown a simple form of guard for the arbor embodying plates 25, 26, 27, and 28, the latter having a narrow slot through it for the passage of the key 20 and movable with it, while the plates 25, 26, and 27 are secured from rotation in the present instance by having at one or both sides lugs or projections 30, entering corresponding recesses formed in the casing 23. 29 indicates a circular washer arranged between the plate 25 and the casing 3. The guard-plates 26 and 27 are each provided with two inwardly-extending segmental lugs 31, having a slot between them, the slot in one extending in a different radial plane from that of the other—in the present instance at right angles—and the lugs being so located that they will engage in the separate recesses 32 and 52 of the key 20. When the key is inserted in a vertical position and moved into engagement with the end of the arbor, the slots 32 and 52 will be brought into line with the lugs 31 on the plates 26 and 27, respectively, and the key may be then turned into horizontal position, and the arms 14 on the arbor closing the door and passing beyond the projections 19, further movement in this direction being arrested not only by the bracket 15 on the arbor, but also by the body of the key opposite the outermost notch 52 engaging one of the wards 31 on the plate 27, the notch between the wards of the plate 26 permitting the withdrawal of the key, however, and leaving the arbor with the door in closed position, as seen in the lower portion of Fig. 1. In order to open the door, the key may be inserted in a horizontal position and turned to a vertical position, revolving the arbor in the opposite direction, but permitting only a half-turn, as the portion opposite the notch 32 in the key will engage with the lower end of the lug 31 on the plate 26. This arrangement of locking thus permits only the proper amount of rotation of the arbor and insures this before the withdrawal of the key is permitted, at the same time permitting the insertion of the key in the proper manner only and limiting its movement.

By constructing the lock-casing with the removable and interchangeable ward or guard plates, as shown, the combination or relative arrangement of the plates may be changed if for any reason this is necessary or desirable, the casing 23 being removed for the purpose, and by reason of the circular openings in the ward-plates the key is afforded a long bearing.

I claim as my invention—

1. The combination with a mail-receptacle having a mail-receiving aperture, of a door for the aperture, a rotatable arbor separate

from but controlling the movement of the door and a removable operating key or handle coöperating with the arbor.

2. The combination with a mail-receptacle having a mail-receiving aperture, of a door for the aperture, a rotatable arbor separate from but controlling the movement of the door, a removable operating-key for engaging the arbor and a guard with which the key coöperates.

3. The combination with a mail-receptacle having a mail-receiving aperture, of a plate pivoted at its lower end and having a flange at its upper end coöperating with the aperture to close it and a series of projections in a lower plane and means for moving the plate on its pivot.

4. The combination with a mail-receptacle, and a casing having a mail-receiving aperture, of a movable door for the aperture arranged within the casing, a removable key for actuating the door having wards and corresponding wards or guards in the casing with which the key coöperates.

5. The combination with a mail-receptacle and a casing having a mail-receiving aperture, of a movable door for the aperture arranged within the casing, a rotatable arbor controlling the door having its operating portion within the casing and key-wards arranged in proximity to the arbor.

6. The combination with a mail-receptacle and a casing having a mail-receiving aperture, of a movable door for the aperture arranged within the casing and a rotatable arbor arranged within the casing and with the coöperating door to hold it in open or closed position.

7. The combination with a mail-receptacle and a casing having a mail-receiving aperture, of a movable door for the aperture arranged within the casing, a rotatable arbor arranged within the casing and coöperating with the door to hold it in open or closed position and having an operating end within the casing adapted to receive a key and a ward-casing on the main casing, detachable fastening devices for the ward-casing and accessible from the inside only of the main casing and wards in the ward-casing arranged adjacent to the side of the arbor-axis with which corresponding wards on a key are adapted to coöperate.

8. The combination with a casing having a mail-receiving aperture, of a movable door for the aperture arranged within the casing, a rotatable arbor also arranged within the casing having portions coöperating with the door to actuate and hold it in open or closed positions and an operating end adapted to receive a key, a ward-casing attached to the main casing, detachable fastening devices for the ward-casing accessible from the inside only of the main casing and a plurality of changeable wards in the ward-casing adjacent

to the operating end of the arbor with which corresponding wards on a removable key are adapted to coöperate.

9. The combination with a casing having a mail-receiving aperture, of a movable door for the aperture, means for actuating said door and holding it in open or closed position, arranged within the casing and adapted to be actuated by a removable key, a ward-casing on the main casing, detachable fastening devices for the ward-casing accessible from the inside only of the main casing, and a plurality of wards in the ward-casing arranged adjacent to said operating means for preventing its operation excepting by the proper key.

10. The combination with the casing having a mail-receiving aperture, of the door pivoted at its lower end in the casing and adapted to control the aperture, the arbor journaled in the casing having the arms coöperating with the door to hold it opened or closed and a removable operating device for the arbor.

11. The combination with the casing having a mail-receiving aperture, of the door pivoted at its lower end and having the projections, the rotatable arbor having arms coöperating with the door to hold it open or closed, a spring for operating the door in one direction and means for rotating the arbor.

12. The combination with the casing having the aperture, of a movable door for the aperture, a rotatable arbor in the casing having an arm coöperating with the door to hold it closed when moved in one direction.

13. The combination with the casing having the aperture, of a movable door for the aperture arranged within the casing, a spring for operating it in one direction, a rotatable arbor having arms or projections engaging the door and holding it open and locked when moved in one direction and closed and locked when moved in the opposite direction.

14. The combination with a mail-receptacle and the casing having the aperture of a pivoted automatically-operated door controlling the aperture arranged within the casing and having flanges at the upper end, the rotatable arbor having an arm engaging the door to close it and a projection coöperating with the door to hold it open.

15. The combination with the casing having the aperture, of a door for controlling the aperture, means for holding the door closed or open, having an operating portion adapted for the application of a warded key, a ward-casing, detachable securing devices for attaching it to the main casing and accessible from the interior only of the latter, and removable and interchangeable key-wards located in the ward-casing and arranged adjacent to the operating means with which the wards of said key are adapted to coöperate.

16. The combination with the casing having the aperture, of a door for controlling the aperture, the operating-arbor for the door adapt-

- ed for the application of a removable key, a ward-casing, detachable securing devices for attaching it to the main casing and accessible from the interior only of the latter, and a plurality of removable ward-plates located in the ward-casing and arranged adjacent the arbor and adapted to coöperate with wards in the removable key.
17. In an operating device for mail-receptacle doors, the combination with a rotatable arbor adapted for the application of a key, of a ward-casing, detachable securing devices for attaching it to the receptacle accessible from the interior only of the latter and a plurality of interchangeable ward-plates located within the ward-casing and adjacent the end of the arbor and having the wards.
18. In an operating device for mail-receptacle doors, the combination with a rotatable arbor adapted for the application of a key, of a casing located adjacent the arbor, detachable securing devices for the casing accessible

from the interior only of the receptacle and a plurality of interchangeable ward-plates arranged in the casing having inwardly-extending wards.

19. The combination with a mail-receptacle embodying a casing having an aperture, of a door for the aperture pivoted within the casing and movable transversely of the plane of the aperture whereby pressure on the door through the aperture will be transmitted to the pivot, and means for operating the door.

20. The combination with a mail-receptacle embodying a casing having a vertical aperture therein, of a pivoted door or closure pivoted beneath and movable transversely of the aperture and between it and the pivot and means for operating the door on its pivot.
